UNITED STATES PATENT OFFICE.

ARTHUR F. REINHEIMER, OF DETROIT, MICHIGAN.

DESIGN FOR A GAME TARGET.

Application filed March 26, 1926. Serial No. 17,063. Term of patent 3½ years.

To all whom it may concern:

Be it known that I, ARTHUR F. REINHEIMER, a citizen of the United States, residing at Detroit, in the county of Wayne and State of Michigan, have invented a new, original, and ornamental Design for Game Targets, of which the following is a specification, reference being had to the accompanying drawing, forming part thereof.

The figure is a plan view of a game target, showing my new design.

I claim:

The ornamental design for a game target, as shown.

ARTHUR F. REINHEIMER.
